UNITED STATES PATENT OFFICE.

WILLIAM O. CUTTER, OF FOXBORO, MASSACHUSETTS.

APPARATUS FOR PROPELLING VESSELS.

1,164,787.

Specification of Letters Patent. Patented Dec. 21, 1915.

Application filed February 16, 1915. Serial No. 8,679.

To all whom it may concern:

Be it known that I, WILLIAM O. CUTTER, a citizen of the United States, residing at Foxboro, in the county of Norfolk and State of Massachusetts, have invented new and useful Improvements in Apparatus for Propelling Vessels, of which the following is a specification.

This invention relates to improvements in apparatus for propelling vessels.

The object of the invention is to provide a simple, economical and powerful apparatus for propelling vessels.

A further object of the invention is to provide an apparatus which shall propel a vessel by discharging fluid under pressure into a pipe or passage arranged longitudinally of the vessel, which fluid creates a movement of the water through said pipe in one direction or the other and discharges said fluid either at the stern or bow of the vessel.

Still another object of the invention is to provide instrumentalities for economically producing the fluid under pressure and for discharging said fluid into the passage in the direction desired.

The invention consists in the combination and arrangement of parts whereby the above objects and certain other objects hereinafter appearing may be attained, as set forth in the following specification and particularly pointed out in the claims.

Referring to the drawings: Figure 1 is a plan view of a portion of a vessel with a device embodying my invention shown in connection therewith, said vessel being broken away and shown in section to save space in the drawings. Fig. 2 is a longitudinal section, partly in elevation, taken on the line 2-2 of Fig. 1. Fig. 3 is a detail sectional elevation taken on the line 3-3 of Fig. 4. Fig. 4 is a transverse section, partly in elevation, taken on line 4-4 of Fig. 1. Fig. 5 is a detail section of the brake mechanism taken on the line 5-5 of Fig. 4. Fig. 6 is a detail perspective view of the brake and clutch operating lever. Fig. 7 is a section taken on line 7-7 of Fig. 2. Fig. 8 is a detail view of the reversible ratchet mechanism for preventing the rotation of the wheel in one direction or the other.

Like numerals refer to like parts throughout the several views of the drawings.

In the drawings, 10 is a portion of a ves-

sel and 11 is a pipe arranged longitudinally of the vessel with a passage 12 extending therethrough and having openings at the bow and the stern of said vessel substantially as illustrated in my prior application for "Device for propelling and steering vessels," No. 855,165, patented May 28, 1907.

The pipe 11 is provided with an explosion chamber 13, which is formed in a casing 14 arranged in close proximity to the pipe 11 and preferably formed integral therewith. The explosion chamber 13 is connected with the passage 12 in the pipe 11 by passages 15 and 16 extending outwardly from said explosion chamber in opposite directions, preferably toward the bow and stern respectively of the vessel.

A gate or valve 17 is interposed between the explosion chamber 13 and the passages 15 and 16 for the purpose of closing one and opening the other of said passages; thus when the explosion occurs in the explosion chamber 13, said gate may be operated to permit the products of combustion to pass from said explosion chamber either through the passage 15 or the passage 16 into the main passage 12.

The gate 17 is preferably formed cylindrical and is arranged to rotate within a cylindrical chamber 18 formed in the casing 14, said gate having ports 19 and 20 which are adapted to be moved to align respectively with the passages 15 and 16, said passages being so arranged in said gate that when one of said ports is in alignment with one of the passages 15 or 16, the other of said ports aligns with the explosion chamber 13. The movements of the gate 17 are controlled by a lever 21 upon the outside of the casing 14, which lever is secured to the rotary gate 17 through one of the end walls 22, 22 of said chamber 14.

The chamber 13 has been hereinbefore designated an explosion chamber and is particularly designed to receive a charge of gas and to permit the explosion of said charge. This chamber however is not limited to the use of a propelling fluid which is exploded, but may be used in connection with any suitable fluids which may be admitted thereto under pressure. The preferred method however is, as has been hereinbefore stated, to admit and explode a charge of gas in said chamber and from whence the products of said explosion are directed into the passage 12 of the pipe 11 in the desired di-

rection by means of the gate 17. Instrumentalities are therefore provided for admitting or governing the admittance of a charge to said chamber and for governing the exploding of said charge. The fuel from which the explosion is produced is conducted to the explosion chamber 13 through a pipe 23 from any suitable source, preferably a tank 24 to which a suitable mixture of gas has been 5 previously supplied. The pipe 23 connects with said explosion chamber through an inlet chamber 25 formed within a detachable cap 26, which has screw-threaded engagement with the casing 14 at 27. See Fig. 4.

15 A valve 28 is interposed between the inlet chamber 25 and the explosion chamber 13 and is preferably of the type known as the puppet valve, said valve having a seat 29 formed in the cap 26. A stem 30 is arranged to reciprocate in the cap 26 through suitable packing 31 secured in place in the cap 26 by a screw cap 32. A spring 33 encircles the valve stem 30 outside of the cap 32 and normally retains the valve 28 in contact with its seat 29. A shaft 34 is journaled to rotate in bearings 35, 35 preferably carried by the pipe 11 and upon said shaft is secured a cam 36, which engages the stem 30 of said valve and at the proper time opens 20 said valve permitting the charge to enter the explosion chamber 13 from the reservoir or tank 24.

Instrumentalities are also provided for igniting the charge, said instrumentalities 35 including a spark plug 37 which is mounted in the casing 14 within which is the chamber 13. Said instrumentalities further include a battery or batteries 38 connected in circuit with the spark plug 37 by wires 39 and 39'. 40 A circuit make and break device 40 is also included in said instrumentalities and includes a switch 41 arranged to be operated automatically by a cam 42 secured to the shaft 34, said cam comprising a disk having notches 43, 43 arranged in the periphery thereof, which notches are adapted to receive a follower 44 secured at the end of the switch member 41 and as the cam 42 is rotated, said follower 44 enters said notches 45 and vibrates said switch.

The switch member 41 is preferably a resilient strip of metal permanently secured at 45 to one of the supports for the shaft 34. A contact 46 is provided on said support and 55 at certain times in the operation of the apparatus said contact is engaged by the vibrator or switch member 41. The make and break 40 is preferably inserted between the wires 39 and 39', one of said wires being connected at 45 and the other at 46; thus as 60 said cam rotates the circuit including said wires 39 and 39' will be opened and closed.

The several instrumentalities for admitting and exploding the charge in the explosion chamber are adapted to be operated by

an electric motor 47, an electric current being supplied to said motor from the battery 38 through suitably arranged wires. The motor 47 is preferably provided with a sprocket 48 which is operatively connected 70 by a chain 49 to the sprocket 50 loosely mounted to rotate about the shaft 34.

The sprocket 50 is adapted to be operatively connected to the shaft 34, when desired, by a clutch 51 hereinafter more specifically described.

In first starting a vessel with an apparatus such as described, the products of combustion or the fluid under pressure is discharged through the pipe 11 in the opposite 80 direction to that in which it is desired that the vessel should move, that is to say, if it is desirable that the vessel illustrated in Figs. 1 and 2 should travel in the direction of the arrow "a," see Fig. 2, the products of combustion must be discharged from the vessel in the direction of the arrow "b." The passage 12 at this time will be filled with water and the impact of the products of combustion from the chamber 13 against said water 90 expels said water from said passage, tending to produce a vacuum.

The tendency of the products of combustion when the vessel is stationary will be to expand in all directions immediately upon leaving the passage 16, thus water will be ejected not only toward the stern, but toward the bow of the vessel until sufficient headway has been maintained by the vessel to produce a movement of water through the 100 passage 12. In starting the vessel therefore it is desirable that an obstruction be provided which will resist the passage of water or the products of combustion through the passage 12 in the opposite direction to that 105 in which the products of combustion are being discharged or ejected from the chamber 13. For this purpose a wheel 52 has been provided, said wheel being rotatably mounted in close proximity to the pipe 11, preferably, within a casing 53 which is constructed as a part of one section of the pipe 11. The axis of the wheel 52 is outside of the passage 12, said wheel having a plurality of radially disposed blades 54 arranged to extend into said pipe or transversely of the 115 passage 12 thereof and to be rotated by the water or fluid passing through said pipe.

A reversible ratchet mechanism 55 is provided by means of which said wheel may be 120 prevented from rotating in one direction or the other according to the direction of movement of the products of combustion from the explosion chamber 13, that is to say, should the products of combustion be discharged 125 in the direction of the arrow "b" the ratchet mechanism will be set so as to prevent the rotation of the wheel 52 in the direction of the arrow "a", but said wheel will be permitted to rotate in the opposite direction, 130

thus a current of water will be produced through the passage 12 in the direction of the arrows "d" permitting water to fill the vacuum or partial vacuum produced in the passage 12 by the rapidly discharging products of combustion.

The ratchet mechanism 55 preferably consists of a ratchet 56 fast to the arbor 57 of the wheel 52. The ratchet 56 is provided with teeth 62 which are adapted to be engaged upon opposite sides by a pawl 58 pivoted at 59 to a stationary portion of the casing 53. The pawl 58 has two arms 60 and 61 arranged to engage opposite sides respectively of the teeth 62 and upon opposite sides of said ratchet. When the arm 60 is engaging said teeth the arm 61 will be out of contact therewith and vice versa.

To insure the proper setting of the reversible ratchet mechanism 55, when the gate 17 is operated, said gate and said ratchet mechanism are operatively connected together preferably by means of a link 63 pivotally connected to the lever 21 and having slidable engagement with a pin 63' on said pawl 58. Springs 64 and 64' are arranged upon opposite sides of the pin 63' within a longitudinal recess 65 formed in the end of said link 63, said recess being closed at the end by a plug 65'. The springs 64 and 64' normally retain the pin 63' central relatively to the longitudinal recess 65, but permit said pin to be moved toward one end or the other of said recess to yieldingly retain one of the arms of the pawl 58 in contact with said ratchet.

The lever 21 is preferably made flexible and works in a slot 102 formed in a plate 99, said plate having ledges 100 and 101 arranged adjacent opposite ends respectively of said slot 102 and against which said lever 21 is adapted to rest, while in its extreme positions, to hold the pawls 60 and 61 in contact with the teeth 62.

In addition to being employed as an obstruction for the water in the pipe 11, the wheel 52 is also adapted to be operatively connected with the shaft 34 to operate said shaft in place of the motor 47, that is to say, after the water passing through the pipe 11 has reached a certain velocity, but until such velocity is reached the movements of said wheel are idle.

The wheel 52 is preferably operatively connected with the shaft 34 by means of a chain 66 engaging a sprocket 67 on the arbor 57, and another sprocket 68 rotatably and loosely mounted upon the shaft 34. A clutch 69 is adapted to be operated to connect and disconnect the sprocket 67 with the arbor 57, while another clutch 70 is adapted to connect and disconnect the sprocket 68 with the shaft 34.

For convenience in operating the apparatus, the clutches 51, 69 and 70 are all oper-

atively connected together in such a manner that when the clutch 51 is thrown into operation, the clutches 69 and 70 are thrown out of operation and vice versa. All of said clutches are preferably constructed in a similar manner.

The clutch 51 preferably consists of a cone 71 secured to a sleeve 72 which is journaled to rotate in a bearing 73 mounted in any suitable manner, but preferably upon the pipe 11. To the sleeve 72 is secured the sprocket 50 which receives its rotary motion from the motor 47.

A collar 74 is secured to the shaft 34 to rotate therewith, said collar having a conical recess 75 arranged to receive the cone 71 of said clutch. A spring 76 is interposed between the collar 74 and the cone 71 within a recess 77, preferably formed in said cone, thus normally retaining said members apart and out of contact with each other. A disk 78 is mounted upon the sleeve 72 between the cone 71 and the bearing 73 and upon said disk are formed projections 79 arranged to engage projections 80 extending outwardly from the bearing 73. When the projections 79 engage the projections 80, the cones 71 will be forced into the recess 75 of the collar 74 and thereby operatively connect the sprocket 50, or in other words, the motor 47 with the shaft 34.

A series of balls 81 are interposed between the disk 78 and the cone 71 to eliminate friction between said members when said clutch is thrown into operation. The clutches 69 and 70 also have cones 71 arranged in conical recesses 75 in the hubs of the sprockets 67 and 68. Springs 76 are also interposed within recesses 77 formed in said cones. The disks 78 are also provided with projections 80 on stationary portions of the frame. The series of balls 81 are also interposed between the members 71 and 78 of said clutches. A link 82 is connected with the disks 78 of the clutches 70 and 69 in such a manner that when one of said clutches is thrown out the other of said clutches will also be thrown out, thus disconnecting said wheel from said shaft.

A second link 83 is operatively connected with the link 82 to be operated simultaneously therewith, said link 83 extending to the clutch 51. This link however instead of being connected directly to the disk 78 of the clutch 51 is attached to the end of the lever 84 which is pivoted at 85 to a stationary bracket 86. A pin 87 secured to the disk 78 of said clutch 51 engages the lever 84 within a slot 88 and as said lever is rocked upon its pivot, said disk 78 will be moved thereby to throw said clutch 51 into and out of operation. This clutch however is connected in such a way that when the clutches 69 and 70 are thrown into operation, said

clutch 51 will be thrown out of operation. An operating lever 89 is connected with the links 82 and 83 and is adapted to move said links from one position to the other to throw 5 said several clutches into and out of operation, said lever being adapted to be locked in its several positions by a pawl 90 adapted to drop into notches 91 formed in the face of a segment 92, said pawl being operated in 10 the usual manner by a hand lever 93.

It is desirable that the shaft 34 be brought to a stop as quickly as possible when all of the clutches are thrown out of operation and to accomplish this result a brake 94 is provided, preferably consisting of a band 95 encircling the collar 74, see Fig. 5, one end of said band being secured to the fixed bracket 86, while the other end thereof is provided with a stud 96 which engages the 20 lever 84 within a slot 97.

When the apparatus is at rest all of the clutches will be thrown out of operation and the brake band 95 will be set against the periphery of the collar 74 and when said 25 parts are in this position, the stud 96 will be in the end of the slot 97, as shown in Fig. 6. Pressure is supplied to said stud by means of said lever to provide sufficient friction for the band 95 against said collar.

30 To further add to the effectiveness of the apparatus the wheel 52 is adapted to be connected with the motor 47 by a sprocket 98, which engages the chain 66, and as said motor 47 is operating through the chain 49 to 35 rotate the shaft 34, the chain 66 will be operated to rotate the sprockets 67 and 68 idly upon their respective shafts. When a sufficient volume of water is being conducted through the pipe 11 and the wheel 52 is being 40 rotated thereby the chain 49 is disconnected by means of the clutch 51 from the shaft 34 and the chain 66 connected with said shaft. At such a time said wheel will operate the motor 47 through the sprocket 45 98 as a generator, merely reversing the action thereof in the usual and well known manner and recharging the batteries.

The general operation of the apparatus is 50 as follows: Assuming that the several mechanisms are at rest and all of the clutches thrown out of operation and the tank 24 filled with the proper fuel, the electric circuit from the motor to the batteries must be closed, setting said motor into operation to rotate the sprocket 50. The lever 84 is then moved by the operating lever 89 in the direction of the arrow "a", Fig. 6, first to release the pressure of the brake band 95 upon the collar 74 which had previously been held by the stud 96 in the end 55 of the slot 97. After the brake has been released a continued movement of the lever 84 in the same direction moves the projections 79 on the disk 78 of the clutch 51 into engagement with the projections 80 on the

bearing 73 thus causing the cone 71 to move into engagement with the collar 74, and as said cone is being rotated at this time by the motor 47, a rotary motion will be imparted to the shaft 34 whereby explosions will be 70 produced within the explosion chamber 13. The gate 17 is then operated to direct the products of combustion toward the forward or rear end of the pipe 11, according to the direction in which it is desired that the vessel should travel. Simultaneously with the operation of said gate the wheel 52 is set to prevent its being rotated in the wrong direction by the force of the explosion in the explosion chamber and the passage of 80 the gases therefrom. The setting of said gate and of said wheel is accomplished by deflecting the lever 21 from its contact with one of the ledges 100 and 101, transversely of the slot 98, permitting said lever to be 85 swung from one of said ledges along the slot 92 to the other of said ledges, and when said lever arrives at the opposite end of the slot 102, the spring thereof will be sufficient to cause said lever to drop behind the ledge at that end of said slot. After sufficient headway of the vessel has been attained and the water is passing through the passage 12 and rotating the wheel 52 at the desired speed, the operating lever 89 is operated to rock the lever 84 still farther upon its pivot in the direction of the arrow "a". This movement of said lever causes the projections 79 of the clutch 51 to move beyond and clear of the projections 80, permitting 90 the spring 76 to retract the cone 71 thus disconnecting the motor 47 from the shaft 34. Simultaneously with the disconnecting of said motor from said shaft the wheel 52 is connected with said shaft by means of the 100 clutches 69 and 70, while the motor continues to operate to generate the electricity and recharge the battery 38, or at least supply sufficient current to ignite the charge in the explosion chamber 13.

When it is desired to stop the vessel the operating lever is reversed with a consequent reversal of the disk 78 of the clutch 51 together with the disks of the other clutches until all of said clutches have been disconnected and the brake band 95 again drawn taut, about the collar 74 thus returning the apparatus to a state of rest.

Having thus described my invention what I claim and desire by Letters Patent to secure is:

1. A propelling apparatus for vessels having, in combination, a pipe arranged longitudinally of the vessel, said pipe having an explosion chamber arranged adjacent thereto and connected by passages extending from said explosion chamber toward the bow and toward the stern of said vessel, instrumentalities for producing explosions in said explosion chamber, means for directing the 125

130

products of combustion through one or the other of said passages, a wheel rotatably arranged adjacent said pipe, a plurality of blades on said wheel arranged to extend into said pipe, and means for locking said wheel against rotation in one direction or the other according to the direction of movement of the products of combustion from said explosion chamber.

2. A propelling apparatus for vessels having, in combination, a pipe arranged longitudinally of the vessel, said pipe having an explosion chamber arranged adjacent thereto and connected by passages extending from said explosion chamber toward the bow and toward the stern of said vessel, instrumentalities for producing explosions in said explosion chamber, means for directing the products of combustion through one or the other of said passages, a wheel rotatably arranged adjacent said pipe, a plurality of radially-disposed blades on said wheel arranged to extend transversely of said pipe, said wheel being adapted to be rotated by the passing of fluid through said pipe, and means for preventing the rotation of said wheel in one direction or the other according to the direction of movement of the products of combustion from said explosion chamber.

3. A propelling apparatus for vessels having, in combination, a pipe provided with an explosion chamber, said chamber being connected with said pipe by passages extending from said chamber toward the forward and rear ends of said pipe, a valve for said explosion chamber adapted to be operated to admit a charge thereto, igniting instrumentalities therefor, means adapted to operate said valve and said igniting instrumentalities to produce explosions in said chamber, a wheel rotatably arranged adjacent to said pipe, said wheel having a plurality of blades extending transversely of said pipe and adapted to be engaged by the passing of fluid through said pipe, and means constructed and arranged to transmit motion from said wheel to said valve and said igniting instrumentalities.

4. A propelling apparatus for vessels having, in combination, a pipe extending longitudinally of the vessel, said pipe having an explosion chamber formed therein outside of the passage through said pipe, said chamber having passages extending therefrom into said pipe substantially in opposite directions, a rotary gate arranged in said chamber and adapted to close one and open the other of said passages, a wheel, a plurality of radially disposed arms on said wheel adapted to project across said pipe, means adapted to prevent the rotation of said wheel in one direction or the other, and means operatively connecting said last named means with said rotary gate whereby

said members may be operated simultaneously.

5. A propelling apparatus for vessels having, in combination, a pipe arranged longitudinally of the vessel and provided with an explosion chamber connected with said pipe by passages extending from said chamber toward the forward and rear ends of said pipe, a gate adapted to close one or the other of said passages, an inlet valve for said chamber, an igniting device, a shaft, means on said shaft adapted to operate said inlet valve and said igniting device to admit and explode a charge within said explosion chamber, an electric motor adapted to rotate said shaft, a wheel rotatably arranged adjacent said pipe and adapted to be rotated by the passing of water through said pipe, said wheel also being adapted to rotate said shaft, and means for connecting said shaft with and disconnecting the same from either said motor or said wheel.

6. A propelling apparatus for vessels having, in combination, a pipe extending longitudinally of said vessel, instrumentalities adapted to inject propelling fluid into said pipe, means for directing said fluid toward the forward or rear ends of said pipe, an electric motor adapted to operate said instrumentalities, a battery adapted to supply current to said motor, a wheel adapted to be rotated by the passing of water through said pipe to operate said instrumentalities to inject propelling fluid into said pipe, said wheel also being adapted to operate said motor to generate electricity, and means for disconnecting or connecting either said motor or said wheel from said shaft.

7. In combination a vessel provided with a passage for water extending longitudinally thereof, instrumentalities adapted to inject fluid under pressure into said passage, means for governing the injection of said fluid into said passage, and a wheel projecting into said passage and adapted to be rotated by the passing of water through said passage, said wheel also being adapted to obstruct the passage of water through said pipe in one direction or the other.

8. In combination, a vessel provided with a passage for water extending longitudinally thereof, instrumentalities adapted to inject fluid under pressure into said passage, means for governing the injection of said fluid into said passage, an electric motor adapted to operate said governing means, and a wheel projecting into said passage and adapted to be rotated by the water passing therethrough, said wheel being adapted to operate said governing means, said wheel being also adapted to operate said motor.

9. In combination, a vessel, a pipe extending longitudinally of said vessel, said pipe having an explosion chamber connected therewith by means of passages extending

from said explosion chamber toward the bow and toward the stern of said vessel, a valve arranged to admit a charge to said explosion chamber, means for igniting said charge in said explosion chamber, a shaft, a cam on said shaft adapted to operate said valve, a second cam on said shaft adapted to operate said igniting means, a motor adapted to rotate said shaft, a clutch adapted to operatively connect said motor with said shaft, a brake for said shaft, and means adapted to operate said clutch to connect and disconnect said motor from said shaft, said means also being adapted to apply said brake to said shaft.

10. In combination, a vessel, a pipe extending longitudinally of said vessel, said pipe having an explosion chamber connected therewith by means of passages extending from said explosion chamber toward the bow and toward the stern of said vessel, a valve arranged to admit a charge to said explosion chamber, means for igniting said charge in said explosion chamber, a shaft, a cam on said shaft adapted to operate said valve, a second cam on said shaft adapted to operate said igniting means, a motor adapted to rotate said shaft, a clutch adapted to operatively connect said motor with said shaft, a brake for said shaft, and a lever connected with said clutch and said brake and adapted to be moved in one direction to throw in said clutch and release said brake, said lever being adapted to be moved in the opposite direction to throw out said clutch and apply said brake.

11. In combination, a vessel, a pipe extending longitudinally of said vessel, said pipe having an explosion chamber connected therewith by means of passages ex-

tending from said explosion chamber toward the bow and toward the stern of said vessel, a valve arranged to admit a charge to said explosion chamber, means for igniting said charge in said explosion chamber, a shaft, a cam on said shaft adapted to operate said valve, a second cam on said shaft adapted to operate said igniting means, a motor adapted to rotate said shaft, a clutch interposed between said motor and said shaft, a wheel arranged adjacent to said pipe and adapted to be rotated by water passing therethrough, a clutch interposed between said wheel and said shaft, and means arranged to alternately throw said clutches respectively into and out of operative positions.

12. A propelling apparatus for vessels having, in combination, a pipe extending longitudinally of the vessel, said pipe having an explosion chamber connected therewith by passages extending from said explosion chamber substantially in opposite directions, means adapted to close one or the other of said passages, a wheel rotatably arranged in said pipe, a plurality of radially disposed blades on said wheel projecting into said passage and adapted to be moved by water passing through said pipe to rotate said wheel, a reversible ratchet mechanism connected with said wheel, and means operatively connecting said ratchet mechanism with said passage closing means.

In testimony whereof I have hereunto set my hand in presence of two subscribing witnesses.

WILLIAM O. CUTTER.
